UNITED STATES PATENT OFFICE.

CARL SIEGENER, OF FRANKFORT-ON-THE-MAIN, PRUSSIA, GERMANY.

HOT-WATER STOVE.

SPECIFICATION forming part of Letters Patent No. 425,711, dated April 15, 1890.

Application filed January 16, 1890. Serial No. 337,103. (No model.)

To all whom it may concern:

Be it known that I, CARL SIEGENER, of Frankfort-on-the-Main, Sacksenhausen, in the Kingdom of Prussia and German Empire, have 5 invented a new and useful Hot-Water Stove, of which the following is a specification, reference being had therein to the accompanying drawing.

The hot-water stove constituting this invention and represented in the accompanying drawing consists of a double-jacketed casing *b*, provided with a fire-grate *g*, and having fitted within it a double-cased hood *e*, which is connected to the main casing *b* by a tube *c*, 10 carried in the form of a worm *d* over the fire-grate and around the hood *e*. Water is admitted by the pipe *a* to the casing *b*, thence passes by the pipe *c* through the worm *d* to the hood *e*, and flows out by the pipe *f*, being 15 heated in its passage through the apparatus 20 by the fire and hot fire gases, which ascend

from the fire-grate *g* through the funnel *h*, circulate within the hood *e*, and passing out around the worm *d* escape by the outlet *i*, the heat being absorbed by the water in the casings *b* and *e* and worm *d*. 25

What I claim, and desire to secure by Letters Patent of the United States, is—

In a water-heating apparatus, the combination of the hollow casing *b*, provided with inlet *a*, the hollow casing *e*, provided with outlet *f*, the funnel *h* within the casing *e* and above the grate *g*, and the worm *d* around the hood *e* and connected with the same and the casing *b*, substantially as described. 30

In witness whereof I hereunto set my hand in presence of two witnesses.

CARL SIEGENER.
